MEANS FOR LUBRICATING MACHINE-TOOLS.

1,065,689.

Specification of Letters Patent.

Patented June 24, 1913.

Application filed December 22, 1911. Serial No. 667,421.

To all whom it may concern:

Be it known that we, EDWARD J. KEARNEY and THEODORE TRECKER, citizens of the United States, and residents, respectively, of Wauwatosa and West Allis, in the county of Milwaukee and State of Wisconsin, have invented certain new and useful Improvements in Means for Lubricating Machine-Tools, of which the following is a specification, reference being had to the accompanying drawing, forming a part thereof:

This invention relates to an extension of or improvement upon the lubricating means covered by United States Letters Patent No. 15 834,063 granted to us October 23, 1906, and particularly to machine tools having substantially vertical spindles.

The main object of the present invention is to provide for the continuous circulation 20 of oil through the bearings of the vertical spindles of such machines and to insure the thorough lubrication thereof without care or attention on the part of the operator.

It consists in the construction, arrangement and combination of parts as herein-after particularly described and defined in the claims.

In the accompanying drawing like characters designate the same parts in both figures.

Figure 1 is a vertical section of a vertical spindle milling machine embodying the invention; and Fig. 2 is a horizontal section of the spindle and its upper bearing on the line 2-2, Fig. 1.

The machine comprises a box frame or hollow case *a*, similar to those of machine tools of this class. It is formed or provided at the upper end with a forwardly projecting hollow arm or extension *b*, which overhangs the work table indicated by dotted lines at *c* in Fig. 1, with which machines of this kind are usually provided. The arm *b* is provided at or adjacent to its front end with vertically aligned bearings *d* and *e* for the vertical tool spindle *f*. The bearings *d* and *e* in the present case are made in the form of flanged cylindrical bushings which are fitted into aligned vertical openings in the arm *b*, and have taper bores. The arm *b* is also formed or provided with a horizontal bearing *g* for a shaft *h*, whose axis is in the same vertical plane with the axis of the spindle *f*. The bearing *g* in the present case consists of a 55 cylindrical sleeve fitted and secured in a corresponding opening in said arm. It is shown as provided adjacent to its ends with bushings *i* of Babbitt or other suitable metal, between which there is an annular 60 oil chamber or cavity *j* surrounding the shaft *h*. Above and parallel with the sleeve *g* the arm *b* is formed with an oil feed or supply passage *k* leading into an oblique passage *l*, which registers at its upper end 65 with a lateral opening through the upper spindle bearing *d*, and at its lower end with an opening through the sleeve *g* into the oil chamber *j*. The spindle *f* is connected with the shaft *h* by bevel gears *m* and *n* inclosed 70 in the arm *b* and accessible through an opening in the front end of the arm, which is provided with a removable closure *o*. From the upper end of the passage *l* above the lower part of the opening through and 75 into the bearing *d*, an overflow passage *p* leads laterally and then downwardly into the space or chamber around the gear *m*, as shown in Figs. 1 and 2. The bore of the upper bearing *d* is formed with one or more 80 longitudinal oil grooves or channels *q*, and the bore of the lower bearing *e* is formed with one or more like or similar grooves or channels *r*. Adjacent to its lower enlarged end inside of the hollow arm *b*, the spindle 85 *f* is formed or provided with an outwardly projecting rim or collar *s*, having a depending marginal lip on the under side, which overhangs an upwardly projecting annular rim or flange *t* on a reducing ring or an- 90 nular closure *u*, removably fitted and secured in the opening in the under side of the arm *b*. The spindle *f* is provided at its upper end with a longitudinally adjustable taper sleeve *v*, fitting into the bearing *d* 95 and secured on the spindle by an adjusting nut *w* for taking up play and wear between said spindle and its taper bearings. The frame or case *a* is formed or provided in the lower part thereof with an oil well or 100 reservoir *x*. A pump *y* having a suction pipe *z* dipping into said well or reservoir, is connected by an upwardly extending discharge pipe *2* with the passage *k*. The shaft *h* is connected by any suitably constructed and arranged train of gearing with a driving shaft *3*, provided with a pulley *4* and gear *5*. In the present case the

shaft *h* is shown as connected with the driving gear 5 through any one of a number of change speed gears 6, which are shiftable lengthwise on a shaft 7 into engagement with corresponding gears 8 on a parallel shaft 9, which is connected by gears 10 and 11 with the shaft *h*, the shaft 7 being connected with the gear 5 by gears 12 and 13.

The power transmitting and speed changing gears with their bearings are supplied with oil when the machine is in operation, as shown and described in our former patent hereinbefore mentioned, by the perforated branch 14 of the oil supply or feed pipe 2, extending across the interior of the frame or case *a* above said gears and bearings, and in the present case connecting the pipe 2 with the passage *k* through which oil is delivered to the upper bearing of the vertical spindle *f* and the bearing of the connecting shaft *h*. A pump of any suitable kind may be used to elevate the oil from the reservoir *x* and deliver it to the gears and bearings to be lubricated. In the present case a rotary pump is shown which is connected with and driven by the main gear 5 of the milling machine. The bushings *i* are formed on the under side of their bores with longitudinal grooves or passages 15, opening at their outer ends into the case *a* and arm *b* respectively, and an opening 16, indicated by dotted lines in Fig. 1, is provided in the wall or partition between the case *a* and arm *b* for the return flow of oil from said arm into said case and thence into the reservoir *x*.

During the operation of the machine, oil is drawn by the pump *y* from the reservoir *x* and forced upwardly through the pipe 2, its perforated branch 14 and the passages *k* and *l*, to the upper bearing *d* of the spindle *f*, and into the annular chamber *j* in the bearing sleeve *g* surrounding the shaft *h*, surplus oil overflowing from the upper end of the passage *l* through the passage *p* and falling on the gear *m*. From the upper end of the passage *l*, oil flows through the opening in the bearing *d* into and through the grooves or passages *q*, thereby thoroughly lubricating said bearing. The surplus oil discharged from the lower ends of the grooves or passages *q*, with the oil discharged from the passage *p*, overflows the gears *m* and *n*, copiously lubricating them, and some of this oil entering the groove or passage *r* in the lower bearing *e*, thoroughly lubricates said bearing, any surplus oil escaping from the lower end of said groove or passage upon the rim *s*, being thrown by centrifugal action away from the joint between the spindle and the ring or closure *u* and thus prevented from escaping through said joint. From the annular chamber *j*, oil flows through the grooves or passages 15 in the lower sides of the bush-

ings *i* and thus keeps the bearings of shaft *h* well lubricated, the surplus oil escaping at the ends of the bushings into the case or hollow frame *a* and its hollow arm *b*, from which it flows with the surplus oil escaping from the spindle bearings *d* and *e* and gears *m* and *n* through the opening indicated at 16, back into said case, and thence down into the reservoir *x*, to be again elevated by the pump *y* and used over and over again.

Various modifications in the details of construction and arrangement of parts may be made in the adaptation of the lubricating means herein shown and described to machines of different kinds under varying conditions, without departing from the principle and scope of the invention.

By the term "vertically alined" or "vertically disposed" as herein employed in connection with the spindle bearings *d* and *e*, and by the term "vertical" as herein employed in connection with the spindle *f*, it is intended to include any inclination thereof at which oil will flow from the upper to the lower bearing.

We claim:

1. In a machine tool the combination of a case or frame having a hollow overhanging arm provided with vertically disposed spindle bearings and an oil passage leading upwardly to the upper bearing, an oil reservoir located in said case or frame below said arm and a pump adapted to elevate oil from said reservoir and to deliver the same through said passage to the upper bearing, the hollow arm and case or frame forming a return conduit for the oil from said bearings into the reservoir.

2. In a machine tool the combination of a case or frame having a hollow overhanging arm provided with vertically disposed spindle bearings, an oil supply passage leading upwardly to the upper bearing and an overflow passage leading from the upper part of said supply passage, an oil reservoir located in said case or frame below said arm and a pump adapted to elevate oil from said reservoir and to deliver the same through said supply passage to the upper bearing, the hollow arm and case or frame forming a return conduit for the oil from said bearings and overflow passage into said reservoir.

3. In a machine tool the combination of a case or hollow frame having a hollow overhanging arm provided with vertically disposed spindle bearings and an oil supply passage leading upwardly to the upper bearing, said bearings being formed in their bores with longitudinal oil channels opening at their lower ends into the case or frame, an oil reservoir located in said case or frame below said arm and a pump adapted to elevate oil from said reservoir and to

deliver the same through said supply passage to the upper bearing, the hollow arm and case or frame forming a return conduit for the oil from said bearings into said

5 reservoir.

4. In a machine tool the combination of a case or frame having a hollow overhanging arm provided with vertically disposed spindle bearings and an oil passage leading to the upper bearing, an oil reservoir arranged in said case or frame below said arm to receive surplus oil flowing by gravity from said bearings into said arm and a pump adapted to elevate oil from said

10 reservoir to the upper bearing through said passage, the hollow arm and case or frame forming a return conduit for the oil from said bearings into said reservoir.

5. In a machine tool the combination of a case or frame having a hollow overhanging arm provided with vertically disposed spindle bearings, a horizontally disposed bearing and an oil passage leading to the upper spindle bearing and to the horizontal bearing, a reservoir arranged in the case or frame below said arm to receive surplus oil flowing by gravity from said bearings into said arm and a pump adapted to elevate oil from said reservoir and to deliver

20 the same to the upper spindle bearing and to the horizontal bearing through said passage, said hollow arm and case or frame

forming a return conduit for the oil from said bearings into said reservoir.

6. In a machine tool the combination of a case or frame having a hollow overhanging arm provided with vertically disposed spindle bearings and an oil supply passage leading to the upper bearing, said bearings being formed with internal longitudinal oil channels opening at their lower ends into said arm, a rotary spindle mounted in said bearings and provided adjacent to its lower end which projects through an opening in said arm, with an outwardly projecting oil deflecting rim or collar overhanging an upwardly projecting rim with which said arm is provided around said opening, an oil reservoir arranged in said case or frame below said arm to receive surplus oil flowing by gravity back through said arm from said bearings, and a pump adapted to elevate oil from said reservoir and deliver the same through said supply passage to the upper bearing, said arm and case or frame forming a return conduit for the oil from said bearings into said reservoir.

In witness whereof we hereto affix our signatures in presence of two witnesses.

EDWARD J. KEARNEY.
THEODORE TRECKER.
